United States Patent Office.

CHRISTINA JULIA MILLER, ADMINISTRATRIX OF CHARLES G. MILLER, DECEASED,
AND BENJAMIN KERSTING, OF SPRINGFIELD, OHIO, ASSIGNEES, FOR ONE-HALF,
TO GEORGE W. HOGLIN AND S. D. GRAFFLIN.

Letters Patent No. 98,700, dated January 11, 1870.

IMPROVEMENT IN HARVESTERS.

The Schedule referred to in these Letters Patent and making part of the same.

To all whom it may concern:

Be it known that CHARLES G. MILLER and BENJAMIN KERSTING, of Springfield, in the county of Clark, and State of Ohio, have invented a new and useful Improvement in Harvesters; and we do hereby declare the following to be a full, clear, and exact description of the same, reference being had to the accompanying drawings, in which—

Figure 1 is a plan of the machine.

Figure 2 is an elevation on line $z z$, fig. 1.

Figure 3, an elevation of ratchet-winch, for raising the cutting-apparatus.

Figure 4 shows the devices for raising, holding, and tripping the rake.

Figure 5, pinion-clutch gear.

Figure 6, bottom plan of rake-carriage.

That others may understand the nature and operation of the invention, we will particularly describe it.

The frame-gearing, &c., does not differ from that described in the patent of Charles G. Miller, March 10, 1868, to which reference is made for description of said parts.

The improvements embraced in this patent relate, first, to the device for raising and lowering the cutting-apparatus; second, to the mechanism for driving the rake; third, to the ratchet-connection of main shaft and driving-wheel; fourth, to the device for raising and lowering the point of the shoe; fifth, to the manner of hanging and bracing the reel-shaft; sixth, to the construction of the reel-blades; seventh, to the manner of arresting and controlling the motion of the rake; eighth, to the manner of adjusting the height of the reel; ninth, to the devices for operating the rake.

A is the main frame, cast in a single piece, and mounted upon the main axle B, by means of the boxes C.

The main frame A is cast with a box or receptacle for tools, which is covered by the hinged foot-board D.

The main driving-wheels E are mounted upon the ends of the axle B, and are each provided with an internal cog-rim, F, which meshes with the pinions G, to drive the cutting and raking-mechanism of the machine.

The pinions G are mounted loosely upon the ends of the pinion-shaft H, which is mounted in suitable boxes, secured to the lower surface of the main frame A, and the dragging-frame I is mounted upon said pinion-shaft, and carries the cutter's crank-shaft J, so that, as the frame I may rise and fall, the crank-shaft pinion will not be out of mesh with its driving bevel-gear K, which is mounted upon the pinion-shaft H.

The dragging-frame I is cast in a single piece, and with a projecting arm, i, through the extremity of

which the drag-bar L passes before entering the rear lug of the inner shoe M.

The drag-bar L is attached, at its forward end, to an arm, a, which is a part of the main frame A, projected around the inner wheel E for the purpose. It passes thence backward, through the front and rear lugs of the shoe M, and causes the cutting-apparatus to advance, when the main frame is advanced. The arm a retains the cutting-apparatus in position, and prevents any lateral movements thereof.

The cutting-apparatus is constructed in any approved manner, and is secured to the inner shoe M in the usual way.

When the machine is operated as a mowing-machine, a track-clearer is attached to the outer shoe; and when it is to be operated as a reaper, the platform N, reel O, and rake P are attached, as shown in the drawing.

To convert the machine from a reaper to a mower, only requires the removal of certain parts, which are described herein, and require no further notice.

When the machine is operated as a mower, the dragging-frame I is let down at its rear end, so that the shoe M will rest and slide upon the ground as the machine is advanced; but when it is required to operate the machine as a reaper, it becomes necessary to elevate and sustain the rear end of the dragging-frame at a proper distance above the ground. It is also necessary to elevate this part of the apparatus suddenly, to avoid some obstruction which may be in the road of the machine.

The lever Q, with its pawl, and the rack R, enables the attendant to raise the cutting-apparatus at any time, the detent S holding the winch at any point, and preventing any retrograde movement of the cutting-apparatus. The cord or chain b serves to connect the winch Q R with the dragging-frame I.

The pinions G are loose upon the ends of the pinion-shaft H, but each of said pinions is provided with a ratchet-face, which engages with the corresponding ratchet-teeth of a collar, T, which is mounted upon the shaft H with a spline and groove, so that it may recede from the pinion, to let the teeth slip past, when the driving-wheel is turned backward.

The spring U is composed of a flat piece of steel, with a hole through its centre sufficiently large to admit the axle-shaft H, and with its ends turned back, so as to rest against the under sides of the journal-boxes of the shaft H, and the heads of the screws which hold said boxes in place. These springs are therefore made in the simplest possible form, and their ends resting against the screw or bolt-heads, and the lower sides of the boxes are securely retained in place, and in proper working position at all times.

The front lug of the inner shoe M is constructed with a vertical slot, through which the drag-bar L passes. The above-mentioned slot permits the front end of the shoe M to be raised or lowered, as may be desired, to give the points of the cutters more or less elevation, and it is retained in the proper position by means of the stirrup V, which encircles the drag-bar, and is attached to the upper end of the forward lug of the inner shoe, by means of two screw-nuts, which permit the vertical adjustment of said stirrup and lug, as above described.

The reel-post W is secured between two flanges, which are cast upon the front lug of the shoe M, so as to make a recess, within which to secure said post. Said flanges extend along the front and rear edges of the post W, and screw-bolts pass through both lug and post, to bind them together.

The post W is curved forward at its upper end, as shown in fig. 2, though this curvature is not considered as essential, and the long box Y is secured at the upper end with a segment-head, c, by means of which the reel may be readily raised or lowered.

The brace d is employed to steady and stiffen the box Y and reel O during operation. It is slotted at its lower end, where it is secured to the side of the front lug of the shoe M by a screw, e, and may thereby be lengthened or shortened, as may be necessary, when the reel O is raised or lowered.

(At its upper end it is attached to the box Y, near the outer extremity thereof, to support and steady it during the operation of the reel.

The reel O is overhung, receiving its entire support from the box Y. It is driven by a pulley, located upon the end of the reel-shaft, and receives its motion by means of a band passing over a similar pulley located upon the main axle-shaft.

The reel-blades are studded, along their front sides, with pointed projections f, for the purpose of straightening out, to some degree, stalks of grain which have become bent down and tangled.

The internal spur-gear wheel g is mounted upon the inner extremity of the main axle-shaft B, and the rake-pitman h' is attached by a wrist to its outer side.

The gear g is driven by a pinion, h, also mounted on the main axle-shaft, and provided with a clutch-key, which is operated by the lever k, and is projected through the hub of the main wheel E and the intermediate wheel l, which is mounted upon the arm m, which is bolted fast to the main frame A.

The function of the wheel l is twofold: it transmits motion from the pinion h to the spur-wheel g, and it also supports said spur-wheel against the strain of the rake-pitman.

By the employment of the wheel l also, both the wheel g and its pinion h can be mounted upon the same axis, and the motion of the rake be properly graduated to the speed of the main wheels.

The pitman h' is connected to the spur-wheel g by a wrist, and at its rear end it is jointed to the rake-carriage n by means of a swivel-pin, o, which permits the pitman to reciprocate without cramping, as the carriage n oscillates upon its pivot p.

The rake-carriage n is cast in a single piece, and is pivoted, at the point p, to the brace q, which extends backward from the shoe M for that purpose.

At its outer end are two rollers, r, which rest and travel upon the segment-track s, as the carriage is moved back and forth by the reciprocations of the pitman h'.

The segment-track s is a flat plate, bent edgewise in the segment of a circle, about the point p, as a centre, so that, as the carriage n moves back and forth around said point, the rollers r will always travel upon the surface of s.

The carriage n is retained in place upon the track s, by fingers or lugs secured to the under side of said carriage, and projected beneath the edge of the track s.

The shaft t is placed upon the upper side of the carriage n, and secured there by suitable journal-boxes u u. The rake-arm is secured, at one end, to the outer end of the shaft t by a square and nut, and at the other end it is bolted to the top of the rake-head P, as shown in fig. 1.

The rake P, in addition to its reciprocation with the carriage n, is capable of a motion upon the axis of the shaft t, as shown in fig. 4, through about one-fourth of a circle. Thus, when it moves backward from the front of the platform, the teeth of the rake rest upon and remove the grain from the platform, but as the rake approaches the rear edge of the platform, the arm v is caused to rise up by a partial revolution of the shaft t, so that the rake is elevated above the platform, as shown in red lines in fig. 4, and it remains in said elevated position until the front edge of the platform is reached, when the rake is permitted to drop and resume its movement backward toward the rear edge of the platform.

The mechanism to produce, at proper times, these movements of the rake, is described as follows:

The arm v is bent downward and backward, as at v' in fig. 4. As the rake-carriage n moves backward, the arm v' comes in contact with the brace w, and the continued movement of the carriage will cause the arm v v' to assume the position shown in red lines in fig. 4.

When said position has been reached, the pin y, on the sliding clutch-collar y', will engage with a notch or hole made for the purpose in the collar t', which is rigidly attached to the shaft t, and the rake will thereby be held in the elevated position described until such time as the pin y' shall be withdrawn from its engagement with collar t.

A spring, s', is coiled about the shaft t, to act upon the collar y', and keep it always in working contact with collar t'. A spring on the lower side of the collar y' rests within a groove in the plate n, as shown in fig. 6, so that said collar is not permitted to have any rotary motion, but can only move in a line parallel with the shaft t.

The trip-lever r' engages with the collar y', and when the carriage n has advanced to the front end of the track s, said trip engages with the brace q, or some other device placed there for the same purpose, and the collar y' is thereby withdrawn so as to release the collar t', and permit the rake to drop upon the platform. It will sometimes happen that the weight of the rake will not alone be sufficient to force the teeth of the rake into the mass of the straw upon the platform. A spring, p', is therefore placed around the shaft t, to act upon the rake, in forcing it to penetrate the gavel, but to retain it in that position while moving backward.

One end of the spring p' is secured to the carriage n, and the other end is secured to a collar, n', which is secured to the shaft t, in any desired position, by the set-screw m'. When, by reason of long use, the spring p' has begun to lose its elasticity, the set-screw m' may be loosened, and the collar n' turned partially around on the shaft, so as to increase the tension on the spring p', and thereby, for a time at least, restore its effectiveness.

The brace q' is adjustable at its outer end either by providing a series of holes in the plate l', (which supports the track s,) into either one of which said brace may be inserted, or a preferable way is to provide a slot, as shown in fig. 4, into which the end of said brace is inserted and secured by a screw-nut. It is necessary to adjust the position of the brace q', in order to regulate the moment when the trip shall be operated and the rake permitted to drop.

In order to reduce the friction incident to the contact of the arm v' and the brace w, a friction-roller, k', is placed upon said brace to receive the arm v', and facilitate the elevation of the rake.

When the attendant desires to throw the rake out of gear, he does so by means of the clutch-key lever *k*, which disengages the wheel *h* from the main wheel *E*. The clutch or shipping-lever *i* serves to disengage the cutter's driving-mechanism from the main driving-wheels.

The arch, upon the top of which is placed the segment-track *s*, is constructed with a frame or plate of metal, *l*, screwed fast to the front and rear lugs of the shoe *M*, and a bent plate of wood, *h'*, which extends from the rear lug of the shoe *M* to the rear end of the segment *s*.

The brace *w* is also provided with a series of adjusting-holes, or with a slot through the arch, so that its outer end may be moved back or forth through a limited degree, to adjust the point of contact between the arm *v'* and roller *k'*.

Thus the braces *w* and *q'* both serve the double purposes of braces to strengthen the arch, and adjustable stops to operate the rake.

Having now described this invention, What is claimed as new, is—

1. The screw-stirrup *V*, in combination with the shoe *M* and drag-bar *L*, for the purpose set forth.
2. The segment-head *Y*, constructed with the reel-shaft box and arms *c c*, as and for the purpose described.
3. In combination with an automatic reciprocating sweep-rake, and its driving-pitman, the wheels *g h*, mounted upon the same shaft, and coupled by the intermediate wheel *l*, all constructed and arranged substantially as set forth.

4. The truck *n*, constructed substantially in the form shown and described, and provided with two friction-wheels, *r r*, to traverse the track *s*, bearings for the rake-arm *v*, and a swivel pitman-joint, *o*.

5. The slotted brace *d*, in combination with the reel-shaft box and the segment-head *c c*, as and for the purpose described.

6. The combination of the rake *P*, mounted upon the shaft *t*, with the clutch-pin *y*, collar *y'*, and trip *r'*, as set forth.

7. The combination of the shaft *t*, spring *p'*, and adjustable collar *n'*, as and for the purpose set forth.

8. The combination of the brace *W*, friction-roller *k'*, and arm *v'*, as and for the purpose set forth.

9. The combination of the arch and segment-track *s* with the rake *P*, carriage *n*, and adjustable braces *w q'*, as set forth.

10. The braces *w* and *q'*, or either of them, when made adjustable at their connection with the arch, so as to serve the double purpose of brace and adjustable stop, as set forth.
